UNITED STATES PATENT OFFICE.

CHARLES H. PEARSON, OF BROOKLINE, MASSACHUSETTS.

FUSE.

Application filed September 22, 1926. Serial No. 137,125.

My present invention relates to fuses and more particularly to improved safety devices therefor.

One of the greatest dangers in handling fuses and the shells to which fuses have been attached is the extreme likelihood of premature discharge because of the detonation of the primer of the fuse. This detonation may occur from a variety of causes, some known and other unknown, and it has been the aim of inventors of this class of devices to produce a safety device which will prevent absolutely the premature detonation of the primer of a fuse, while yet allowing the primer and the fuse to operate properly and at the desired time to cause an explosion of the shell. In my development of this art I have devised several improved and novel means by which this desirable result may be accomplished and one of such means is disclosed and claimed in the patent granted to me, No. 1,543,232, dated June 23, 1925. In my present invention I have described several and further improved forms of devices for accomplishing this desirable result. In my present invention I have provided preferably a removable plug fitting into a recess or passage extending through the wall separating the detonating chamber of the fuse from the chamber or recess in which is located the timing train and in such removable plug I have formed a primer chamber, which primer chamber maintains the primer always in alinement with the firing pin operated and controlled by the timing train. Associated with the removable plug and on either side of the primer held in the primer chamber, I arrange movable members which normally shield the primer from the action of the firing pin and also shield the charge in the detonating chamber from the flash of the primer due to the premature detonation thereof. These movable members are operable under the influence of centrifugal force to move into such a position relative to the primer chamber and the firing pin that access to the primer is provided and also the passage extending from the primer to the detonating chamber is cleared. These movable members may be connected together for simultaneous movement or may be separated from each other and each capable of independent movement, and further, such members may be rotatably mounted on an axis lying parallel to the longitudinal axis of the fuse or such members may

be slidably mounted in a radial direction under the influence of centrifugal force. Again, such members are yieldingly held in such a position as to prevent contact of the firing pin with the primer and to prevent access to the detonating chamber of a flash from the primer and when the device is operated under the influence of centrifugal force into position to allow the firing pin to strike the primer, the movable members are preferably locked in such position.

The object of my present invention, therefore, is an improved safety means for fuses and the like.

In the accompanying drawings illustrating preferred embodiments of my invention,

Fig. 1 is a vertical, central sectional elevation of a fuse body to which my invention has been applied;

Fig. 2 is a sectional plan view on the line 2—2 of Fig. 1;

Fig. 3 is a sectional plan view on the line 3—3 of Fig. 1;

Fig. 4 is a fragmentary sectional plan view, similar to Fig. 2 but with a part shown in and out of position;

Fig. 5 is a sectional plan view on the line 5—5 of Fig. 1;

Fig. 6 is a vertical, central, sectional elevation of a fuse body showing a modification of my invention applied thereto;

Fig. 7 is a plan view on the line 7—7 of Fig. 6;

Fig. 8 is a fragmentary, vertical, central sectional elevation showing the primer plug of Fig. 6 in another position;

Fig. 9 is a perspective view of the movable member illustrated in Figs. 6, 7 and 8;

Fig. 10 is a plan view of a portion of a fuse showing a modified form of construction of a safety member, and

Fig. 11 is a sectional elevation on the line 11—11 of Fig. 10.

Referring to the drawings, and particularly to Figs. 1 to 5 inclusive, 10 designates a fuse body provided on its upper end with an annular recess 11 in which is a circular holding device 12 for holding a fuse cap 13 thereon against longitudinal movement while yet permitting rotary movement of such fuse cap. The upper end of the fuse body 10 is recessed at 14 to receive timing mechanism 15 but when the apparatus is designed to be an impact fuse, such timing mechanism 15 may be omitted. The lower end of the body 10 is ex-

100

105

110

ternally threaded at 16, such threading 16 screwing into a shell body. The lower end of the fuse body 10 is recessed at 17 and the outer end of this recessed portion is threaded at 18 to receive the externally threaded plate 19. There is a considerable body of metal 20 separating the recesses 14 and 17 and such body 20 is perforated as indicated at 21, the lower portion of this perforation 20 being threaded to receive an externally threaded primer plug 22. The primer plug 22 is slotted, as indicated at 23, to provide a flat passage in which is loosely fitted a baffle plate 24. Rotatably mounted in the plug 22 and centrally thereof is a shaft 25, to which is secured the baffle plate 24 and to the top of this shaft 25 is also secured a baffle plate 26, the upper surface of this baffle plate 26 lying slightly below the lower surface of the recess 14. Extending through the plug 24 is a flame passage 27 and at the upper end of the flame passage is formed a primer holding chamber 28, in which is ordinarily fitted the usual primer 29. The baffle plate 26 is provided with a cut-out portion or groove 30 that is in alignment with a perforation 31 in the baffle plate 24 and ordinarily the baffle plates 26 and 24 are so positioned with respect to the flame passage 27 as to bring the groove 30 and perforation 31 out of alignment therewith. Associated with the timing mechanism 15 is a firing pin 32 that is in vertical alignment with the primer 29 and passage 27, which is ordinarily prevented from coming in contact with the primer 29 by the baffle plate 26. The normal position of the baffle plate 26 is shown in Fig. 2, where anti-clockwise movement beyond a certain point is prevented by such baffle plate engaging with the pin 32 secured to and extending upward from the plug 22. Also secured to and extending upward from the plug 22 is a pin 33, to which is secured one end of a U-shaped spring 34, the other end of this spring engaging with the baffle plate 26, as shown, and tending to hold a baffle plate 26 against the pin 32. Fig. 4 shows the operated position of the baffle plate 26 and the spring 34 tends to hold the baffle plate 26 in its operative position with the groove 30 thereof in alignment with the flame passage 27. The spring 34, therefore, holds the baffle plate 26 either in open or closed position. The baffle plate 24 being secured to the shaft 25, and, therefore, 55 movable simultaneously with the baffle plate 26 and perforation 31 in such baffle plate 24 being in alignment with the groove or cut-out 30 in the baffle plate 26, when the baffle plate 26 is in the position shown in Fig. 4 with the groove 30 therein in alignment with the flame passage 27, there will be provided a through passage from the recess 14 to the flame chamber 17. The primer 29 being in a stationary member, there is no danger of premature detonation such as sometimes occurs when mov-

able primer holders are employed. The baffle plate 26 is so constructed as to be overbalanced in certain respects and the assembly of the baffle plates 24, 26 and the shaft 25 will, during the rotation of the fuse body 10, 70 caused by the rifling in the gun from which the fuse is fired, rotate the assembly of the baffle plates 24 and 26 in a clockwise direction or from the position shown in Fig. 2 to the position shown in Fig. 4. 75

If the primer 29 has, for example, been in the fuse for a considerable length of time, it may be desirable to remove the same and substitute therefor another and fresher timer. In order that this may be done without disturbing the setting of the timing train 15, I have arranged the plug 22 so as to be screwed into the body 20 between the recesses 14 and 17 and have provided the end face of the plug 22 with radially spaced depressions 35, these depressions receiving a spanner and by means of which the plug 22 may be inserted in or withdrawn from the fuse body 10 and this without disturbing the time fuse 15 in any way. 80

While ordinarily there is no danger of flame passing downward from the primer 29 beyond the baffle plate 24 and through the flame passage 27 in the detonating chamber 17, yet to insure an easy path for the passage 95 of flame from such primer under abnormal conditions, I have formed that portion of the baffle plate 26 normally over the primer 29, as indicated at 36 in Fig. 1. This formation of the baffle plate 26 at this point will allow 100 flame caused by the detonation of the primer 29 to be deflected upward and outward around the timing train 15 rather than to be forced downward around the baffle plate 24 and through the flame passage 27. 105

Referring now to Figs. 6 to 9 inclusive, 10 designates the fuse body having at its upper end the annular recess 11 in which is an annular holding device 12 for holding a fuse cap 13 thereon against longitudinal movement while yet permitting rotary movement of such cap on the body. As was described on reference to Figs. 1 and 2, the fuse body 10 is provided with an internally threaded perforation 21 and in which is fitted a screw 115 plug 40. This screw plug 40 is provided with a passage 41 extending entirely through the same and in alignment with the firing pin 32 that is controlled by the timing mechanism 15. This passage 41 is enlarged at its upper end to provide a primer chamber 28 in which is fitted a primer 29. Perpendicular to the passage 41 and diametrically arranged with respect to the plug 40 and arranged above and below the primer 29, are recesses 42 and 43 125 respectively. Slidably mounted in the recess 42 is a pin or shaft 43^a, one end of which is provided with a longitudinal recess 44 and the other and lower end of which is provided with a notch 45. On the side opposite the 130

notch 45 is formed a flat face 46 and engaging with the flat face 46 is a depressed portion 47 formed by forcing a portion of the material of the plug 40 into the recess 42. The engagement of the projection 47 with the flat face 46 prevents rotary movement of the rod 43^a in the recess 42. Intermediate the ends of the bar 43^a and perpendicular to the face 46 is a perforation 48, which, when the bar 43^a is moved to the left of Fig. 6, under the influence of centrifugal force or into the position shown in Fig. 8, brings the perforation 48 into alignment with the passage 41. Fitting into the recess 44 is one end of a coil spring 49, the other end of this coil spring engaging with the bottom of the recess 42 and this coil spring 49 tends to hold the bar 43^a in the position shown in Fig. 6 or with solid material in alignment with the firing pin 32 and, therefore, when the bar 43 is in the position shown in Fig. 6, there is no possibility of the firing pin 32 being allowed to come into engagement with the primer 29. Slidably mounted in the recess 43 is a second bar 43^a and in this instance the flat face 46 is on the bottom, as viewed in the drawings, and engaging with this new bottom face 46 is a projection 50 formed by forcing up the material of the plug 40 into the recess 43. When in the position shown in Fig. 6 and the bar 43^a is held in this position by the spring 49, solid material lies across the passage 41 and when, under the influence of centrifugal force, the spring 49 is compressed and the bar 43^a moves into the position shown in Fig. 8, the passage 48 therein will be in alignment with the passage 41 and flame from the detonating primer 29 will be allowed to flow through the passage 41 and into the detonating chamber 17. By reference to Figs. 6 and 8, it will be noted that the notches 45 in the bars 43^a are opposite each other, and also, it will be noted that the plug 40 is provided with a passage 51 that lies parallel to the flame passage 41. In such passage 51 are latches 52 and between these latches is a coil spring 53, this coil spring tending to force the latches 52 upward and downward respectively or from the position shown in Fig. 6 into the position shown in Fig. 8. The outward movement of the latches 52 can only take place when the bars 43^a are moved from the position shown in Fig. 6 to that shown in Fig. 8 and it will be obvious that having reached the position shown in Fig. 8, the latches 52 will act as means for locking the bars 43^a in such position so that after the shell comes to rest, it will still be possible to detonate the same under the control of the timing mechanism 15.

Referring now to Figs. 10 and 11, there is shown a further modification of my invention and in this modification the fuse body 10 is provided as formerly with a screw plug 54. In this case the plug 54 is not as thick as the thickness of the wall in the fuse body 10 but

such plug is provided with a flame passage 55 and with a primer chamber 56 at the upper end thereof. The screw plug 54 is centrally drilled to receive as a driving fit a pin 57 that lies parallel to the axis of the fuse body 10 and rotatably mounted on such pin 57 is one of the plates 26 and associated with this plate 26 is a spring 34 mounted on the pin 33, this spring 34 acting as above described with reference to Figs. 1 to 5 to lock the plate 26 in either the position shown in Fig. 10 and, where the primer chamber 56 is covered or in such position that the cut-out portion 30 thereof exposes the primer chamber 56 to view or to the action of the firing pin 32. The screw plug 54 is provided with a transverse slot 58 similar to the transverse slot 23 in Fig. 1 and that portion of the plug 54 below the slot 58 is drilled to receive as a rotating fit the body of the plug 59. The plug 59 has a slotted head 60 formed at its lower end and also at its upper end which is reduced in diameter, as indicated at 61, and on this reduced portion is slidably mounted a protecting plate 62 which is similar in outline to the plate 24 described with reference to Figs. 1 to 5 inclusive. The portion of the member 59 adjacent to the reduced portion 61 has coiled thereabout a spring 63 and one end of this spring fits into a slotted recess on the lower face of the plate 62 while the other end fits into a hole or perforation in the member 59. By rotating the member 59 the tension of the spring 63 may be varied at will and, therefore, the tension on the plate 62 varied at will. When this tension is all that is desired, a headless screw 64 in the plug 54 is forced against the body 59, thus holding the same against movement and maintaining the tension on the spring 63. The member 62 has associated therewith a spring identical with the spring 34 and this spring 34 is mounted on an extension of the pin 33. The spring for the members 62 and the extension of the pin 33 are not illustrated and it is thought that this construction will be obvious from the present description. In the form of my device shown in Figs. 10 and 11, the protecting members located above and below the primer chamber are independently movable and are spring operated and spring held in the extreme operated position.

It will be obvious from the above that I may, within the limits of my invention, have a device arranged practically in duplicate on either side of the primer holding chamber and these duplicate devices may be either connected together to work as a unit or may be independently operable either in a rotary or a sliding manner, the rotary device being illustrated in Figs. 10 and 11, while the sliding devices are illustrated in Figs. 6 to 9 inclusive.

The operation of my improved device will be obvious from the above description and it

will be obvious also that I may vary the size, shape, and arrangement of parts comprising the device within relatively wide limits without departing from the invention.

5 Having thus described my invention, what I claim as new is:

1. A safety device for fuses having a detonating chamber, a primer chamber and a passage flame leading from said primer chamber to the detonating chamber of a movable member in said fuse interposed between the primer chamber and the detonating chamber and extending transversely of the flame passage, a second member associated 10 and simultaneously movable with the first member, said members being movable by centrifugal force to expose the primer in the primer chamber to the action of the firing pin and to clear the flame passage.
- 15 2. A safety device for fuses having a detonating chamber, a primer chamber and a passage leading from said primer chamber to the detonating chamber of a movable plate in said fuse interposed between the primer chamber and the detonating chamber and extending transversely of the flame passage, a second plate associated and simultaneously 20 movable with the first plate, said plates being movable by centrifugal force to expose the

primer in the primer chamber to the action 30 of the firing pin and to clear the flame passage.

3. An improved primer plug for fuses comprising a body member, a primer chamber formed therein, a flame passage in said body member, a rotatably mounted centrifugal operable shutter on said member normally preventing access to the primer chamber and blocking means associated therewith and located in the body member intermediate 40 the ends thereof.

4. An improved primer plug for fuses comprising a body member, a primer chamber formed therein, a flame passage in said body member and a rotatably mounted plate 45 associated therewith and mounted in the body member and normally blocking the flame passage, a centrifugal operable rotatable shutter on the body member normally preventing access to the primer chamber, 50 said rotatably mounted plate being provided with a perforation adapted to be brought into alignment with the flame passage in the body simultaneously with the rotation of the shutter for the primer chamber.

In testimony whereof, I have signed my name to this specification.

CHARLES H. PEARSON.
